ART OF AND APPARATUS FOR LIQUID
TREATMENT

George Moore, Croton on Hudson, N. Y.

Application October 13, 1934, Serial No. 748,243

25 Claims. (Cl. 210—24)

In the art of treating liquid for improving its condition, such for instance as the contacting of water with zeolites to render the water soft, it has heretofore been proposed to regenerate or 5 restore to effectively operating condition the base-exchange material by supplying to it a quantity of regenerative agent sufficiently exceeding the requirements of the base-exchange material to be sure of the restoration or regeneration 10 at the expense of undue waste of excess quantities of the regenerative agent.

This invention relates to the art of treating liquid with a base-exchange material and the restoring or regeneration of such material, and to 15 apparatus for facilitating the practicing of the art in an effective and economical manner.

To this end, an important object of the improved art is the delivery of a measured quantity 20 of the regenerative agent to the zeolites or other base-exchange material to assure effective regeneration without substantial or appreciable waste of the salt or other regenerative agent; and another object is the timing of the steps of the art to afford maximum efficiency in the supplying 25 of softened water or other treated liquid at minimum expense.

This invention also relates to apparatus for the treatment of liquid for improving or modifying its condition wherein the capacity of the apparatus is limited in the quantity of liquid of 30 which it is capable of treating as a continuous operation, and it is an object of the present invention, when the limit of such capacity is reached, to automatically restore the apparatus 35 for enabling continuation of the treating operation.

Illustratively applied to a specific instance, the invention is particularly applicable to apparatus for the softening of water through the use of 40 base-exchange material, and an essential object of the present invention is the automatic regeneration of the water softening agent upon exhaustion thereof.

Another object is the supplying of a measured 45 quantity of regenerative agent proportioned to satisfy, without appreciably exceeding, the requirements of the base-exchange material to effectively regenerate the same.

A further object is the effective delivery of 50 regenerating solution by gravity when and as required, and more specifically by difference in specific gravity between such solution and water.

In greater detail, a further object is the production of apparatus capable of periodically 55 generating zeolites, or the like, at intervals less

than the period of exhaustion of such zeolites whether measured by time or by the quantity of water softened, and restoration of the water softening process relation of the parts by means timed relative to such exhaustion period. 5

In greater detail, an object of the present invention is the supplying of soft water inexpensively, whether in large quantities or for domestic use, and under conditions either wholly avoiding interruption in the supply of soft water or reducing the interruption to minimum and timing it to afford least possible inconvenience for the user. 10

With these and other objects in view as will in part hereinafter become apparent and in part be stated, the invention comprises liquid treating 15 apparatus and timing means therefor for treating a quantity of liquid, then restoring the treating means to condition for further operation, and then continuing the treating operation.

The invention in greater detail comprises the 20 said apparatus wherein the treating means is a base exchange material.

The invention also includes liquid supply and discharge devices or mains and means for controlling intake and discharge of liquid to such treating 25 apparatus for timing the operations thereof.

The invention still further comprises certain other novel constructions, combinations, and arrangements of parts as subsequently specified and 30 claimed.

In the accompanying drawings,—

Figure 1 is a substantially diagrammatic showing of apparatus embodying the features of the present invention, parts being seen in section.

Figure 2 is a diagram of the relative positions 35 of valves during successive operations of the apparatus, the letter "o" being used to indicate "open", the letter "c" being used to indicate "closed", and the word "normal" being employed to describe that condition where the soft water 40 or other treated liquid is flowing or free to flow for consumption by the user.

Figure 3 is an enlarged, detailed, fragmentary, vertical section through the zeolite tank of Figure 45 1 shown on an enlarged scale, the intermediate parts being broken away to save space, and parts being seen in elevation.

Figure 4 is a vertical section of the upper portion of the salt tank modified by being supplied 50 with baffles to prevent upward diffusion of salt solution.

Figure 5 is a transverse section taken on the plane indicated by line 5—5 of Figure 4, and looking downward. 55

Figure 6 is a view in side elevation of the timing apparatus.

Figure 7 is a front edge view thereof, parts being broken away and shown in section.

5 Figure 8 is a sectional elevation, largely diagrammatic, of a modified embodiment of the structure seen in Figure 1.

Figure 9 is a view similar to Figure 1 of a somewhat modified embodiment of the apparatus.

10 Figure 10 is a front edge view of the parts seen in Figure 9.

Figure 11 is a vertical section taken on the plane indicated by line 11—11 of Figure 10, parts 15 being seen in side elevation, and the operating levers being omitted with a showing only of their pivotal connections to the cam.

Figures 12, 13, and 14 are diagrammatic views 20 showing the successive positions of normal, salting, and rinsing, respectively, of the tank of the structure seen in Figure 9.

Figure 15 is a diagrammatic, vertical, substantially central section through the said tank, the 25 intercommunicating pipes between the compartments being shown in elevation as a matter of diagrammatic license, but they are not in fact in the plane of the section and are actually located spaced as seen in Figure 12.

Figure 16 is an enlarged, detailed, sectional 30 elevation of one of the trunnion mountings or bearing supports of said tank.

Figures 17, 18, 19, and 20 are diagrammatic showings of the valves in the said trunnion mountings with dotted line showing in Figures 35 18 and 19 of the respective adjusted positions during successive operations for effecting non-registration and registration for liquid transfer within the container, and supply and discharge of liquid to and from the container, the several 40 valves being shown in the sequence reading from left to right of Figure 15.

Figure 21 is a fragmentary, side elevation of a modified form of a control lever arm.

Figure 22 is a cross section therethrough on 45 the plane indicated by line 22—22 of Figure 21.

Figure 23 is a view similar to Figure 1 of a modified embodiment of the invention.

Figure 24 is a vertical section of a fragment 50 of the container structure of Figure 23, parts being seen on an enlarged scale, and parts being broken away for the saving of space.

Figure 25 is an enlarged, fragmentary section through a part of the apparatus showing the pressure equalizer tube control valve and connections of the structure seen in Figure 23.

Figure 26 is a similar view of the regenerative agent control valves and connected parts.

Figure 27 is a diagram of the relative positions of valves of the structure seen in Figures 60 23 to 26 inclusive.

Figure 28 is a diagrammatic showing of a modified embodiment of the timing mechanism seen in side elevation.

Figure 29 is a fragmentary end view of a portion thereof on an enlarged scale.

Figures 30 and 31 are cross sections on lines 30—30 and 31—31 of Figure 28, the parts being seen on an enlarged scale.

Referring to the drawings by numerals, and 70 more particularly to Figures 1 to 7 inclusive, 6 indicates a tank for containing the base exchange material, such as zeolites, 7. For convenience of description and reference, but with the understanding that other liquids may be 75 otherwise treated for affording desirable results,

water and its treatment for being softened will be mentioned in the following description with the reservation that such mention is illustrative. A main supply or intake pipe 8 is branched to provide a branch pipe 9 leading into the upper end 5 portion of the tank 6, and a branch 10 leading to and communicating with the upper end portion of a tank 11 for the regenerating material or liquid, such as brine. A control valve 1 is located in the branch 9 and a control valve 2 is located in 10 the branch 10. The branch 9 is further branched at 12 to serve as a discharge pipe or drain, and the branch 12 is provided with a valve 3. A discharge pipe 13 leads from the lower portion of tank 6 for delivering the softened or otherwise 15 treated water or liquid, and the pipe 13 may be considered the regular water service pipe for a house, hotel, or other place of use of the softened water. A pressure check valve 14 is preferably located in the pipe line 13 to prevent back flow 20 from house and to insure against discharge of liquid through the pipe except under pressure. The brine tank 11 is preferably disposed above the tank 6, and is provided with a communicating pipe 15 leading from the lower end or bottom of 25 tank 11 to the lower end portion of tank 6, and the upper end of the pipe 15 communicating with tank 11 is provided with a valve seat within the tank against which rests a valve 4, when valve 4 is in its closed position. A salt tank 16 is 30 located at an elevation above tank 11, and has its lower end communicating by a pipe 17 with the lower end or bottom of tank 11. The free end of the pipe 17 in tank 11 terminates in a valve seat with which a valve 5 cooperates. The valves 35 4 and 5 are preferably pivoted to and freely pendent from a rocker arm 18 with which an eccentric or cam 19 is adapted at times to engage to depress that end of the rocker arm 18 carrying the valve 5. Valve 4 is sufficiently 40 weighted to overbalance the valve 5, and, therefore, to be seated whenever the cam 19 is raised and thereby allows the valve 5 to move from its seat. Cam 19 is carried by a rock shaft 20 extending through the wall of tank 11 and provided 45 with a crank arm 21 outside of the tank. An operating link 22 engages the crank arm 21 to actuate the same, as will be hereinafter described. The tank 16 is provided with a screen or other foraminous plate 23 spaced from its lower end, so 50 that the tank may contain a supply of salt or other appropriate material 24 while allowing only clear brine or other liquid containing dissolved material 24 to occupy the space within tank 16 below the screen 23. A filler tube 25 extends 55 through the upper closed end of tank 16, and is preferably closed by a removable cap 26 threaded into the exposed upper end of the filler tube 25. A pipe 27 communicates through the closed upper end of tank 16 and extends upwardly there- 60 from and then down to and communicates with the upper end of the tank 11. A valve 6' is located in this pipe to close this passage off during the washing operation as hereinafter described, insuring that the water will pass through tank 11, 65 pipe 15, tank 6 and out drain 12. A pressure equalizing pipe 28 connects with the pipe 27 at its highest portion and extends down to and communicates with the upper end of the tank 6.

The valves 1, 2 and 3 are provided with operating levers 29, 30, and 31, respectively, and are counter-weighted at 32, 33, and 34, respectively, so that when one of the levers is depressed the respective valve will be opened or closed, and when the lever is released the counter-weight will 75

close or open the valve, and the weights 32, 33, and 34 are preferably sufficient also to restore the actuating parts hereinafter described to their respective initial positions when the respective levers 29, 30, and 31 are released.

Timing mechanism hereinafter described is employed for operating the valves 1, 2, 3, 4, 5 and 6' when and as required for effecting a regenerating operation at the termination of a predetermined period, and such period may be determined in units of hours or other time units, or may be determined in units of quantity of liquid treated.

The operation is capable of being carried out manually, but for precision, inexpensiveness, and dependability is preferably mechanically carried out by the timing mechanism seen in outline in Figure 1, and in greater detail in Figures 6 and 7.

An appropriate frame 35 is provided in which is journaled a cam 36 having a spur gear 37 located to at times mesh with the teeth 38 of a mutilated gear 39. Gear 39 is fixed to an actuating shaft 40, which may be driven by a time clock, not shown, or by apparatus hereinafter described with respect to Figures 10 and 11. When the time clock is used and the apparatus is employed for domestic purposes, the timing is such that the valves 1, 2, 3, 4, 5 and 6' will be operated according to the diagram of Figure 2 for salting and rinsing once in twenty-four hours, and in order to provide the requisite time for the salting and for the rinsing and proportion it properly, a mutilated gear is used, so that the cam 36 will be stationary for a large portion of the rotation of the gear 39, say seven-eighths, and, therefore, the cam will move comparatively rapidly during the time when it is moving and yet actually accomplish only one complete revolution in twenty-four hours. Of course, by "rapidly" is only meant rapidly in the comparative sense with respect to the speed it would possess if it moved constantly and achieved a complete revolution only once in twenty-four hours. The object of this will become apparent in a consideration of the operation of the apparatus.

The periphery of the cam 36 is engaged by a roller 41 journaled between the arms 42 of a cross bar 43. Cross bar 43 has its ends fixed to up-standing rods 44 which are also fixed to a cross bar 45 at their upper ends. A piston-like rod 46 depends from the cross bar 45 and carries a weight 47 within a cylinder 48 which is preferably filled with oil or other liquid 49. A port 50 is formed vertically through the piston-like weight 47 to allow flow of the liquid 49 through the weight as it descends, so that the structure functions as a dash-pot and causes the cross bar 45 and its connected parts to descend gradually rather than with a sudden drop, whereby the delivery of a blow or shock incident to the dropping of the roller 41 from the periphery of the cam 36 at its widest radius to the periphery of the said cam at its narrowed radius is avoided. The arms 42 are provided with lateral flanges 51 outstanding beyond the planes of the cam 36, one in position to actuate a link or bar 52, and the other in position to actuate a link or bar 53. The former, extending to the left as seen in Figure 7, is herein identified as the left flange 51, while the other is called the right flange 51. Bar 52 at its lower end portion is pivotally connected by links 54, 54 with the free ends of the arms 29 and 31 of valves 1 and 3. Bar 53 at its lower end portion is pivotally connected by link 55 with the lever 30 of valve 2, and the said bars 52 and 53

are successively depressed by the dropping of the flanges 51 and their connected parts from the greatest radius of cam 36 to the smallest radius thereof. In order to divide up the movement and time the same as required for the operation to be accomplished, the cam 36, inward of its periphery, carries operating levers 56 and 57, each stressed by a spring 58 fixed to the cam and located and engaging the respective lever for returning the lever to the normal position seen in Figure 6 when the lever is released. Each lever 56 and 57 is pivoted at 59, and has its opposite or free end portion curved at 60 to correspond approximately with the arc of a circle whose center is the axis of the cam 36, and whose radius is the distance from said center to the free end of the lever when depressed. In order to impart motion from the left flange 51 to bar 52, an outstanding arm 61 projects from the bar 52 to a position beneath lever 56, and the lever 56 is located at one side of cam 36 in the line of said flange as the flange descends, so that the flange, when descending, will strike the lever 56 and cause it to depress the arm 61 and bar 52 and hold the bar depressed while the flange 51 is traversing the curved portion 60 of lever 56. The lever 56, however, is not depressed sufficiently to allow the roller 41 to reach the shortest radius of cam 36 with the first drop. To avoid this, the cam 36 is provided with a stop 62 in the path of the lever 56 at about midway between the greatest and the least radius of the cam 36. Thus, as the roller 41 begins to make its descent, the lever 56 depresses bar 52 a distance sufficient to move the lever 31 of valve 3 to the opened position of the valve and lever 29 of valve 1 to the closed position of the valve. A rod 63 extends upward from and is carried by the bar 52 and pivotally engages a bell crank or other appropriate lever 64, which has its other arm pivoted to a link 65 that engages a bell crank or other appropriate lever 66, which last-named bell crank lever is pivoted to the link 22. An extension link 65' connects to one arm of the bell crank 66', the other arm of which connects with the vertical rod 66a in turn connected with arm 66b of valve 6'. Thus, when the bar 52 is depressed by the movement of lever 56 down to engagement with the stop 62 and the valve 1 is thereby closed and valve 3 opened, the crank 21 is at the same time turned to cause the cam or eccentric 19 to depress the rocker arm 18 and thereby seat the valve 5 while opening the valve 4.

The movement of the cam 36 is sufficiently slow to cause the left flange to contact along the moving curved portion 60 of lever 56 throughout a time period sufficient for accomplishing the salting or regenerating impregnation of the base exchange material 6, and the opening of valve 4 and closing of valves 5 and 6' with valves 1 and 2 closed and valve 3 open enables this impregnation operation to occur by gravity. When the regeneration is completed, the movement of cam 36 will be such as to cause the left flange 51 to drop off of the free end of lever 56 and allow the lever to rise to the position seen in Figure 6. As the left flange 51 drops off of lever 56, the right flange 51 drops onto the lever 57, depresses it, and contacts along the curved portion 60 of the latter lever as it travels with the moving cam 36. The weight of the roller and its connected parts causes the depression of lever 57. It will be readily seen that the right flange 51 engages the lever 57 and depresses it. The bar 53 is provided with a lateral arm 67 extending

beneath and in the path of the lever 57, so that, as lever 57 descends, the bar 53 will swing the lever 30 of valve 2 and thus open the valve. An arm 68 extends laterally from bar 52 at a lower portion of the bar, and an arm 69 extends laterally from the bar 53 and is of sufficient length to overlie the arm 68, as seen in Figures 1 and 7, so that, when the roller 41 moves off lever 56 and onto lever 57, the lever 56 moves upward under the action of its spring 58 to its normal position. However, the bar 52 is held against such upward movement by the engagement of arm 69 with arm 68. The arms 68 and 69 are so located that when the bar 53 is in its lowered position holding the valve 2 open, the bar 52 will be held sufficiently lowered to retain valve 1 closed and valve 3 open. The retaining of the bar 52 in its lowered position also retains the link 22 raised and valve 5 depressed to its seat so that valve 4 will be open and valve 5 closed. Thus, when water is entering from the main 8 through the branch 10, through tank 11, past valve 4, and through pipe 15 to the tank 6, the valve 1 will be closed, valve 2 open, valve 3 open, valve 4 open, and valves 5 and 6' closed. Thus, the regenerating solution is washed out of the bed 7 and caused to flow out through the drain 12 during the time while the right flange 51 is contacting along the curved portion 60 of lever 57. When the right flange 51 drops from the lever 57 to the periphery of the cam 36 near its shortest radius, the lever 57 will return under the action of its spring 58 to the raised position of Figure 6, except, of course, that the cam has progressed angularly away from the line of the flange. With such return movement, the bar 53 rises under the force of the weight 33 and the bar 52 rises under the force of the weights 32 and 34, so that the parts are restored to their normal positions with the valve 1 open, valve 2 closed, valve 3 closed, valve 4 closed, and valves 5 and 6' open. The parts will maintain this relation throughout the next period of delivering softened water until in the operation of the timing mechanism the cam 36 has completed another revolution and the levers 56 and 57 are again depressed, as just described. It will be observed that by the use of the cam 36 a substantial weight carried by lever 41 may be gradually lifted with the use of minimum power to afford adequate force for the required valve operations to cause the complete regenerating process, including the salting and washing operations.

The curved portion 60 of lever 58 is preferably longer than the curved portion 60 of lever 57, because the former controls the time for introduction and functioning of the regenerative agent, the brine, while the latter controls the introduction and operation of the cleansing or wash water, and the former requires a substantially greater time than the latter. For instance, in some apparatus such as used for domestic supply, five minutes is sufficient time for the washing operations; whereas the salting or regenerating operation will ordinarily require ten minutes or longer. In this connection there is seen in Figures 21 and 22 a slightly modified embodiment of the curved portions 60 of levers 56 and 57 to enable such curved portions to be varied in their effective length, according to variation in time required for any particular installation or use. To that end, the curved portion 60' is made up of a rigid connection and a movable section 60'' telescopically mounted

thereon. The telescoping action and means for fastening the section 60'' at any predetermined point in the length of the section 60' may assume any of numerous readily available forms, one of which is seen in cross section in Figure 22. The section 60' is seen as a transversely U-shaped member with the opening upward and a lateral internal tongue 177 extending into the longitudinal groove of the section 60' which is U-shaped in cross section and mounted to extend 10 within the space surrounded by the U-shaped body of slide 60'', so that the parts 60' and 60'' are secured against lateral or edgewise separation. A set screw 178 extends through one wall of section 60'' into engagement with the section 15 60' to clamp the two together against telescopic movement during use. By the employment of such an extensible curved portion 60 on each of the levers 56 and 57, the timing may be adjusted as found most desirable, and varied according to the requirements of the particular installation.

It will also be observed that the sequence of valve operations is fully and accurately shown in the diagram as seen in Figure 2, from which the 25 operation will be readily followed in the reading of the drawings.

Salt 24 is introduced into the tank 16 through the filler tube 25 by the removal of the cap 26 when and as required, and the tank 16 is maintained normally with a supply of brine sufficient for supplying the brine tank 11 when and as required. The capacity of the brine tank 11 is preferably made variable in any appropriate manner. One efficient and inexpensive method of 30 varying the said capacity is by providing quartz pebbles 10, or other appropriate non-active substance capable of being introduced in greater or less quantities into the tank 11 when and as required. A filler opening in the upper end of tank 40 11 is closed by a removable plug or cap 11a. An appropriate screen or other support 11 is preferably provided in the tank 11 to support the pebbles or other displacement articles 10.

In the regeneration of the base exchange material as heretofore practiced, when applied for example to zeolites, it has been the practice to supply the required salt in the form of a salt solution, and in order to insure complete restoration of the zeolites to best water softening condition, the gauge employed has been the time during which the brine has been caused to flow through the zeolites. This method has proved inaccurate and wasteful. Contrasted therewith, the present invention measures the actual 45 amount of salt to be used, causes thorough penetration of the zeolites by the brine, and allows opportunity for the regeneration to occur, and then washes out the exhausted salt solution. This automatic measurement of the actual 50 amount of salt to be used for restoration of a given bed of zeolites has proved highly satisfactory and is an important factor of the present invention. The brine as employed in the present invention is approximately a saturate solution, and, therefore, each cubic foot of brine always contains the same amount of salt. Therefore, the measurement may be accurately made within a reasonable margin of safety without appreciable waste. A completely saturate salt solution is not preferable because of the possibility of crystallization of salt therein which is objectionable as hereinafter explained.

It will be observed that during the operation when the parts are in what has been called the 75

normal position, that is the position delivering softened water through the pipe 13, the valve 5 will be open and valve 4 closed. Pressure at both sides of both valves 4 and 5 is equalized at all times by pipes 15 and 28, so that relative movement of the brine is accomplished by gravity, and more particularly by difference in specific gravity. During the time of normal operation, when water is being delivered from the main 8 through the branch 9 to the top of the zeolite bed 7 and down through the said bed and out through the pipe 13, brine will drop through pipe 17 to and fill the tank 11 up to the equalization point somewhere along the pipe 27. The upper extremity of pipe 27 and the upper end of tank 16 will, however, contain clear water free from brine. When the timing mechanism changes the relative positions of the valves for the salting operation, as shown by the diagram in Figure 2, the valves 1 and 2 will be closed and valve 3 open. Opening valve 3 relieves the pressure in tank 6 and accordingly valve 14 automatically closes. Also, valves 5 and 6 will be closed and valve 4 opened, so that the brine in tank 11 can drop by difference in specific gravity to the lower part of tank 6 and work its way up through the bed 7 of zeolites. Equalization through pipes 28 and 27 insures the displacement by difference in specific gravity and resulting effective regeneration of the bed 7. During this time, no water flows through pipe 13, since the valve 14 does not open except under pressure, and there is no appreciable pressure in tank 6 during such regeneration operation. When the regeneration is completed and the timing mechanism makes another shift of the valves, the washing or cleansing operation begins, and, for that purpose, the timing mechanism retains valve 1 closed but opens valve 2 and leaves valves 3 and 4 open and leaves valves 5 and 6 closed. Thus the wash water entering from the main passes through the branch 10 up to the upper end of the tank 11 and washes all of the remaining brine, if any, down through pipe 15 and up through the bed 7 and out through the drain 12. Still during this operation no water is discharged through pipe 13 because the open condition of drain 12 relieves the tank 6 from any such pressure as will open the valve 14. During this time of washing, the valve 5 being closed, no brine can enter the tank 11 from pipe 17. When the cleansing or washing operation is completed, as controlled by the timing mechanism, the valves are again shifted so that the supply of water past the valve 2 is cut off and water is delivered to the tank 6 through the branch 9. The valve 5 again being open and the tank 11 being equalized in pressure but otherwise quiescent is in condition to receive brine from tank 16 through pipe 17, and the brine will fill the tank 11 by difference in specific gravity, whereby the water in the tank is caused to move up the pipe 27 and into the tank 16 sufficiently to replace brine delivered to the tank 11.

In Figure 3 is seen in detail the preferred embodiment of the tank 6, though, of course, it is within the spirit and scope of the present invention to employ any of various forms and structures of tanks adaptable for the purpose. An object of the present invention is to obtain highly efficient results with as inexpensive apparatus as practicable, and in carrying out that object the tank 6 instead of being porcelain lined or made of Monel metal, as is readily available where the expense is not an objection, the tank is lined with sheet rubber 72 which covers the inner sur-

face of the cylindrical portion of the tank and is preferably fitted into circumferential grooves 73 in the top and bottom cover plates 74, the said cover plates being similarly lined with rubber, as indicated at 75. The top and bottom cover plates 5 are preferably clamped together against the cylindrical portion of the tank by securing rods 76, having clamping nuts 77 thereon, and, as a convenience of construction, the rods 76 are preferable extended below the lower cover plate 74 to 10 provide supporting feet 78 for the tank. Of course, the rods 76 may be extended through any appropriate or available portions of the cover plates 74, but where the said plates are comparatively heavy, as, for instance, where they are made of 15 cast metal, perforated ears 79 are preferably provided for the passage of the rods 76. The pipes 12, 13, 15, and 28 which communicate with the tank 6 are preferably provided with appropriate screens for the filtering of the liquids passing 20 through the respective pipes, and the said screens while capable of assuming any of various forms are preferably provided in the nature of extension tubes 80, each slotted as indicated at 81 with the slits of sufficiently thin or fine gauge for serving 25 for screening purposes. By the use of such extension tubes 80 wire mesh screen is avoided with its objectionable possibility of lodgment and accumulation of substances at the place of intersection of the wires. Furthermore, the extension tubes 30 80 are preferably readily detachably applied so as to be readily renewed when required and also readily removed and cleansed when needed. The inner extremity of each extension tube 80 is preferably closed by an appropriate removable plug 35 preferably threaded into place within the tube, as indicated at 82. Each extension tube is of sufficiently less diameter than the threaded portion 83 of the respective pipes 12, 13, 15, and 28 which is threaded into and through a portion of the 40 respective cover plate 74 to allow the respective extension tube 80 to be withdrawn when the threaded section 83 is unscrewed from its engagement with the respective cover plate 74. Each extension tube 80 is preferably threaded into the 45 respective threaded portion 83 so that it is readily detachable and easily cleansed and replaced.

While the pipe 27 in extending upward from tank 16 insures against brine finding its way into the uppermost portion of the pipe 27 or into the 50 pipe 28, as a further guard against any such possibility baffles may be employed in the upper portion of tank 16 to prevent upward movement of brine and to insure that clear water will be present in the upper end of the tank 16. A form of 55 such baffles is seen in Figures 4 and 5 wherein the tank 16 has its filler tube 25 closed by the cap 26, and appropriately connected to or formed integral with the tube 25 are baffle plates 84 proportioned to fit snugly within the tank 16. When 60 the tank 16 is cylindrical, as seen in Figures 4 and 5, the baffles 84 will be in the form of discs with a relatively small notch 85 formed at one place in the periphery of each disc, and the notches 85 of the several discs will preferably be 65 staggered at diametrically opposite sides of the tank 16 for the successive baffle plates 84, as plainly seen in Figures 4 and 5.

In Figure 8 is shown a modified embodiment 70 of the treatment apparatus of Figure 1 in which the salt tank is nested within the zeolite tank, and the brine tank assumes the form of an enlarged tube leading directly from the salt tank, the parts being otherwise arranged to function substantially as above described. In the em- 75

bodiment of Figure 8, 86 indicates the zeolite tank containing the bed of zeolites 87, and also containing a salt tank 88 having a comparatively enlarged tube 89 serving as a brine tank. A 5
 5 filler tube 90 extends through the upper end of tank 86 and through an opening 91 in tank 88 to enable salt to be delivered to the tank 88 from time to time as required. Tube 90 is of sufficiently smaller diameter than opening 91 to 10
 10 permit liquid to enter tank 88 about tube 90. A foraminous support or screen 92 is arranged in tank 88 to support the salt therein and leave a brine space at the lower end of the tank communicating with the pipe 89. A rock shaft 93 15
 15 having an intermediate portion formed into a crank 94 is journaled in the upper end portion of the tank 86 and has a portion extending beyond the tank and provided with a crank 95. A counterbalance weight 96 is fixed to the shaft 20
 20 93 at the outer portion thereof in position for moving the shaft 93 angularly in a direction for moving the crank 94 to a non-salting position while the crank 95 is designed to be operated to move the crank 94 to the salting position. A link 25
 25 97 is pivoted to the crank 94 and depends therefrom through the tank 88 and throughout the tube 89 to a point below the tube where it carries a valve 98, so that, when the crank 94 is raised by the oscillation of shaft 93, the valve 98 30
 30 is caused to be seated against the lower end of the tube 89 and close said tube, and thus prevent delivery of brine from the tube to the area in tank 86 occupied by the zeolites. Crank 95 is engaged by a link 22' corresponding in connections to the timing operation and in functioning to the link 22 of the structure seen in Figure 1. A supply pipe 8' leads from the main and is provided with a branch 10' communicating with the lower end portion of tank 86 and 40
 40 with a branch 9' communicating with the upper end portion of tank 86. A drain pipe 12' leads from the branch 9'. A valve 2' is arranged in the branch 10', a valve 1' is arranged in the branch 9', and a valve 3' is arranged in the branch 12'. The prime marks are here used 45
 45 solely to indicate that a different structure is being described, but the main numbers, eliminating the prime marks, correspond to corresponding parts in Figure 1, and the operation of these several valves 1', 2', and 3' is the same as the valves 1, 2, and 3; whereas valve 98 takes the 50
 50 place of both valves 4 and 5. The same timing mechanism may be used for actuating the valves 1', 2', and 3', and the operation will be substantially the same as that above described. Briefly, it consists, when the parts are in normal position with the valve 98 closed, valve 3' closed, valve 2' closed, and valve 1' open, of introducing water through branch 9' to the upper end 55
 55 of tank 86. The water filling the tank descends through the zeolites 87 and is discharged out through the delivery pipe 13' past the pressure valve 14'. When the timing mechanism reaches the point for regeneration, the valve 1' is closed 60
 60 and valve 2' is left closed, valve 3' is opened, and valve 98 is opened. Thus, by difference in specific gravity the brine will descend through the tube 89 and rise through the zeolite bed 87 until equalization occurs. There will be clear 65
 65 water at the upper end portion of tank 86 and at all times the opening 91 will permit sufficient entry of water to the tank 86 to maintain brine within said tank. As soon as the salting or regenerating operation is completed, the timing mechanism operates to shift the valves so that 70
 70 75

valve 1' remains closed, valve 2' is opened, valve 3' remains open, and valve 98 is closed. Then water flows from the main through branch 10' past valve 2' to the bottom portion of tank 86 and rises through the zeolite bed, washing the 5
 5 brine therefrom, and discharging it out through the branch 12'. As soon as this washing or cleansing operation is completed, the timing mechanism restores the valves to the position where the valve 1' is open, and valves 2', 3' and 10 10
 10 98 are closed. Discharge of softened water through pipe 13' will then proceed until the time for another regenerating operation.

In Figures 9 to 20 inclusive is illustrated an embodiment of the present invention having as 15 an essential object the employment of the water meter as the source of actuation for the timing mechanism instead of the use of a timing clock or like actuator such as is well adapted to be used with the above described apparatus. The 20 water meter may, of course, be that employed regularly for measuring the quantity of water passing through a pipe or main at any given point, or it may be a special meter provided for the purpose of actuation of the instrumentalities 25 hereinafter described, and will preferably be the latter form of meter wherever there is any objection to taking power from the water meter in regular use. The use of such meter as a source of power for actuating the timing cam has the 30 advantage of causing the regeneration operation to occur timed not according to hour periods, but according to quantity or bulk of water treated, so that the approach of exhaustion of the capacity of the zeolite bed, or bed of other 35 base exchange material, may be used to govern the time of regeneration rather than an arbitrary selection of a time period which may be far short of the exhaustion of the softening capacity of the base exchange material or may be 40 so near the complete exhaustion as to allow passage of some hard water. Of course, with apparatus as above described where the timing is determined thus arbitrarily, as, for instance, with clock mechanism set to rotate the cam a 45 complete revolution in twenty-four or forty-eight hours, the zeolite bed will be proportioned to the average use or consumption of soft water with a substantial margin of safety. Where the apparatus is used for domestic purposes and a 50 clock mechanism actuates the timing cam, the cam is preferably set to cause regeneration at some hour, say two o'clock a. m. when there is less likelihood of need for a water supply; and, since the regeneration process from its start until the cleansing is completed will usually require about half an hour, the cutting off of the house supply is not ordinarily noticed or in any sense objectionable, but if in any special case it did become objectionable, a special by-pass 55 can be provided to allow the water to be drawn directly from the main during the period of regeneration. Such a by-pass is seen in Figure 9, as will be hereinafter described.

It will be readily understood that where the timing cam is actuated by the water meter, provision must be made for continuing the movement of the cam after the beginning of the salting operation and until its completion by means other than the water meter, since the water meter is 60 inactive and no water flows during the salting period, and, to that end, it is desirable to provide a supplemental motive power which might assume any of various forms, such as power stored from the water meter and released when 65 70 75

the water meter is rendered inactive by the salt-
ing operation, or as the use of electric power as
shown in Figures 9 and 10.

While, of course, the timing cam actuated by
5 the water meter may be applied readily to ap-
paratus such as described above, it is also well
adapted for application to a somewhat different
set of apparatus where gravity or the difference
in specific gravity is used as the means for af-
10 fording the requisite interchange of liquids and
the desired permeation or percolation of the re-
generative liquid through the base exchange ma-
terial.

In the embodiment seen in Figures 9 to 20 in-
15 clusive, a container or tank 99 is provided similar
to the tank 86 to the extent that each encloses
both the zeolite bed and the salt, but these tanks
differ in details of construction and method of
operation. Tank 99 is journaled to oscillate, and
20 when in the position which may be called "nor-
mal" in the sense of delivering softened water,
the tank is in its upright position, as seen in
Figure 12, or is free to be oscillated from that
position through 135° to the substantially in-
25 verted inclined position of Figure 13, and from
such inclined position is adapted to be swung
back to the inclined position of Figure 14, which
is 45° from the vertical. The tank 99 is pro-
vided with laterally extending trunnions 100,
30 one at each side of the tank and each finding
bearing on a support 101. As one convenient
mode of maintaining assemblage and supporting
engagement, the trunnions 100 are formed with
their exposed faces provided with circular de-
35 pressions into which extend the laterally pro-
jecting disc-like bosses of the supports 101. The
said trunnions 100 and supports 101 not only
serve to sustain the tank 99 and allow oscilla-
tions thereof, but also serve as valves, and, to
40 that end, the support 101 at the left of the con-
tainer 99, as seen in Figure 15, is provided with
ports 102 and 103 with which communicate the
pipes 104 and 105, respectively. The pipe 104
45 is the service pipe for delivering the softened
water to be used, while pipe 105 discharges to
the drain. Cooperating with the ports 102 and
103 are ports 106 and 107 through the trunnion
100 at the left of the container 99, as seen in
50 Figure 15. The other trunnion 100, that is the
one at the right as seen in Figure 15, is pro-
vided with ports 108 and 109 which cooperate
with a port 110 in its respective support 101.
A supply pipe 111 communicates with the port
55 110 and leads from the water main or other ap-
propriate source of supply.

Within the tank 99, a partition 112 is provided
which divides the tank into an upper and a
lower compartment, viewing the structure in the
upright position of Figure 12. The upper com-
partment is supplied with zeolites 113 or other
60 appropriate base exchange material, and screens
114, 114 are preferably arranged at the respec-
tive ends of the bed of zeolites to provide a
space 115 at the upper end of the upper com-
partment, and a space 116 at the lower end of
65 the upper compartment beyond the bed of zeolites
113. The lower compartment of tank 99 contains
a bed of salt or other appropriate regenerating
material 117, and screens 118 are arranged at the
upper and lower ends of said bed to provide a
70 lower space 119 and an upper space 120 beyond
the ends of the bed of salt 117. A tube 121 leads
from the space 119 through the bed of salt 117,
space 120, partition 112, and opens into the space
75 116. Likewise, a tube 122 leads from the space

115 through the bed of zeolites 113, space 116,
partition 112, and opens into the space 120. These
tubes 121 and 122 may be located at any de-
sired position within the container 99, but are
preferably arranged substantially at opposite 5
points 90° around the tank from trunnions and
diametrically opposite each other as seen in Fig-
ure 12. Their location in Figure 15 is merely
indicated diagrammatically and is not intended
to follow any definite plane of section, since if 10
such definite plane were followed, one of the
tubes would be entirely omitted and the other
would be seen in dotted lines. Communicating
with port 109 is a tube 123 which extends up-
wardly within the tank 99 and communicates 15
with the space 115. A tube 124 communicates
with the port 108 and extends downward and
communicates with the space 116. The refer-
ence to "upward" and "downward" assumes the
normal or upright position of tank 99. A tube 20
125 communicates with the port 107 and extends
upward within the tank 99 and communicates
with the space 115. A tube 126 communicates
with port 106 and extends downward within the
tank 99 and communicates with the space 116. 25

It will be readily understood that the tank
99 may be manually oscillated, but for depend-
ability in the operation of the parts timing mech-
anism is employed for actuating the tank for
effecting the regenerating and cleansing or wash- 30
ing operations periodically as required, but the
action of the device as a treatment device for
liquids may be readily understood independently
of any mechanism for swinging the tank and ir-
respective of the details of such mechanism. 35

When the tank 99 is in the position seen in
Figures 12 and 15, it is in regular operation and
water is flowing in through pipe 111, through
port 110, through port 109, and pipe 123 to the
space 115. The water then percolates down 40
through the bed 113 to the space 116 from which
it rises through pipe 126 and passes through port
106 and port 102 and out through the house
service pipe or other delivery pipe 104. This op-
eration continues for the established period, pref- 45
erably somewhat short of exhaustion of the ze-
olites 113. The column of water in the pipe 122
is clear water and the brine confines itself with-
in the lower compartment. So long as the tank
99 remains in the upright position, the normal 50
operation of liquid treatment will continue and
the supply of softened water through pipe 104
remains available. Notwithstanding the pres-
ence of a body of brine in the lower compartment
immediately below the space 116, there is no 55
danger of intermingling, since the difference in
specific gravity assures maintenance of the salt
within its own compartment so long as that com-
partment is below the level of the zeolite com-
partment. 60

When it is desired to regenerate the zeolites,
it is only necessary to swing the container 99
upon its pivotal mounting from the upright pos-
ition of Figure 12 through approximately 135° to
the substantially inverted but inclined position 65
of Figure 13. In moving thus angularly, the
several ports of trunnions 100 will have been
moved from the full line position of Figures 18
and 19 to that dotted line position indicated by
the arrows and marked 135°. It will be noted 70
that the two ports 106 and 107 when moved
135° as seen in Figure 18 will face a blank por-
tion of the cooperating part of the valve and
will not be in register with either port 103 or
102. Likewise, the ports 108 and 109, after mov- 75

ing 135°, will face a blank portion of its respective cooperating part of the valve and neither will be in register with the port 110. Thus, by swinging the tank 99 through 135° to the position seen in Figure 13, the supply and the discharge communications will be entirely cut off, and the only action which can occur is internal and is not interfered with by outside communication. It will be understood, of course, 5 that there is a body of brine in what normally is the lower compartment, but has temporarily become the upper compartment. This brine flows down the pipe 122 to the space 115, and by difference in specific gravity displaces the water 10 in that space and works its way up through the zeolite bed 113, displacing the water therefrom. The water thus displaced is moved up through 15 the pipe 121 to the space 119 where it contacts with the salt bed 117, and this action continues 20 until either the tank 119 is swung away from the inverted position or until equalization occurs with the zeolite bed saturated with brine. The timing mechanism used preferably provides for allowing sufficient time for such saturation so as 25 to insure full regeneration of the zeolites. It will be noted that the displaced water in entering the salt compartment provides a body of brine for the next operation and so on throughout successive operations, the water supplied through 30 pipe 122 to the space 120 being only the initial operation.

As the salt of bed 117 becomes exhausted, it may be replenished from time to time, and to facilitate its introduction, a tube 26a is preferably provided leading through the end of the tank 99 and through the screen 118 and closed by a detachable, preferably screw-threaded cap 26b.

When the salting operation has been completed, the tank 99 is swung pivotally back to the position seen in Figure 14, which is approximately 45° from the vertical. On reaching this position, that port 108 will come to register with the port 110 and also port 107 will come to register with port 103, so that the tube 124 receives a supply from the main line 111, and the pipe 126 discharges into the drain pipe 105. Therefore, as long as the tank 99 remains in the inclined position of Figure 14, there will be a washing or cleansing operation consisting of a flow of water from pipe 111, through port 110, and port 108 and pipe 124 to the space 116, and thence in a generally upward direction through the zeolites 113 to the space 115, and thence 45 through the pipe 125 to port 107 and port 103 and out through the drain pipe 105. This reverse flowing, that is flow in a reverse direction through the bed 113 from the normal advance of water being softened not only removes the saline 50 solution but removes any foreign particles collected on the upper screen 114 and in upper portions of the zeolites as a result of filtering action from previously supplied water being softened. Thus, the zeolites 113 are not only regenerated, 55 but are thoroughly cleansed, and this action continues until the zeolites are entirely freed from salt. Then the container 99 is swung the remaining 45° back to its upright or normal position as seen in Figure 12, and the parts are thus restored for normal operation in the delivery of 60 softened water.

The reverse cleansing flow just described is of value in freeing the zeolites of sediment and slime, and a similar cleansing flow is used in each 65

of the other forms herein disclosed to wash out foreign substances.

It will be readily understood that the oscillations of the tank 99 may be accomplished by any of various forms of timing mechanism appropriately coordinated with the functioning of the tank and its cooperating parts. One preferred embodiment of such timing mechanism is seen in detail in Figures 9 to 11 inclusive.

A timing cam 127 similar in construction and arrangement to cam 36 is provided and engaged by a weighted roller 128 similar to roller 41 and having the same detailed equipment as shown and described with respect to Figures 6 and 7, so that repetition is not required. However, in view of the actions required, the cam 127 is preferably provided with three levers indicated at 129, 130, and 131, respectively, instead of being provided with the two levers 56 and 57 as seen in Figures 6 and 7. The cam 127 is carried by a shaft 132 which is supplied with ratchet wheels 133 and 134. Wheel 133 is engaged by a pawl 135 stressed into such engaging position by spring 136 carried by a crank arm 137, to the outer end of which crank arm the pawl 135 is pivoted. Crank arm 137 is fixed to a shaft 138 extending from and driven by the water meter 139. The meter 139 may be either the regular house meter or other regular service meter, or it may be a similar, special meter used solely for the supplying of power proportioned to the quantity of water utilized. It will be obvious that with the running of the meter 139 the ratchet wheel 133 will be revolved or advanced angularly (since the movement is comparatively slow), and the cam 127 will be correspondingly moved so long as the meter 139 is in operation.

As above stated, during the operation of the tank 99 and its contained parts, there is a period of salting while the tank is in its substantially inverted position when no water is drawn from the main, and during that period the meter 139 will be inactive. If, therefore, no other provision were made, the cam 127 would remain stationary and the tank 99 would not be restored from its salting position. To move the tank from such position, so that the flow of water through meter 139 will be reestablished, an appropriate electric motor is preferably utilized, as indicated at 140, whose circuit 141 is adapted to be closed and broken by a switch 142 actuated by a lever 143 operated by fingers 144, 144, outstanding from a rod 145 which extends down past the cam 127 and is provided with a lateral finger 146 in the path of one of the flanges of the weighted part 55 sustained by roller 128 on cam 127, whereby when the cam allows the roller 128 to drop from the greatest radius of the cam toward the shortest radius thereof, the lever 129 is depressed, say for approximately one-third the distance between 60 said greatest radius and shortest radius. The rod 145 is thus thrust downward and as its lower end is pivotally connected to an operating lever 147 of a valve 148 in a branch 149 of the main line 111, the said valve 148 will be opened by the 65 first step in the drop of the weighted roller 128. Lever 147 is counterbalanced by a weight 150 which closes the valve as soon as roller 128 rolls off of lever 129 and allows the same to rise to its normal, outward position.

Stops 62a similar to stop 62 are provided to limit the descent of the several levers 129, 130, and 131, as seen in Figure 9.

Branch 149 communicates with the lower end of a cylinder 151, seen diagrammatically in Fig- 75

ure 9, and which contains a piston head 152 connected by a piston rod 153 to a rack bar 154. The upper end of the cylinder 151 is sufficiently open to allow the piston head 152 to travel freely upwardly for producing an up stroke of the rack 154 incident to the inflowing of water under pressure from the branch 149. A gear 155 meshes with the teeth of the rack 154 and is fixed to the tank 99 at the plate of one of its trunnions, so that, when the rack 154 is reciprocated, the tank 99 is oscillated. The cylinder 151 is of sufficient length to allow the piston 152 to have the requisite travel under the force of water supplied through branch 149 to impart to the rack 154 the requisite stroke to move the tank 99 through an arc of 135°. As this is the maximum angular adjustment of tank 99, the gear 155 may be mutilated to the extent of having only sufficient teeth to give the required angular movement. The salting operation, of course, will begin just as soon as the tank 99 has been inverted by the action of piston 152 incident to the opening of the valve 148. Since the meter 139 ceases operation as soon as the tank 99 has been thus inverted, the electric motor mechanism above described is provided, and the downward stroke of the upper finger 144 will swing the lever 143 for closing the circuit 141 and starting the motor 140. The motor is, of course, geared for the requisite timing, so that the cam 127 is caused to move sufficiently for causing the roller 128 to move across the outer end portion of lever 129 during the required time for salting, and when that time has been completed the roller 128 drops off of lever 129 and onto lever 130. Incident to this action, the valve 148 is closed by weight 150, and the rod 145 is moved upward so that the lower finger 144 moves the lever 143 upward and breaks the circuit 141. Thus, the motor 140 ceases to operate when the tank 99 is brought to the cleansing or washing position where further water is drawn through the meter 139. Thus when the roller 128 drops off of lever 129, the motor 140 ceases to actuate cam 127 and meter 139 begins again to actuate the cam. At the same time, the roller 128 strikes and depresses the lever 130 which in turn strikes a lateral pin 156 extending from a rod 157 which extends down and is pivoted to a lever 158 of a valve 159 in a branch drain pipe 160 which extends to and communicates with the cylinder 151 above the lower end thereof and sufficiently below the upper extremity of the stroke of piston 152 to represent a 90° movement of tank 99. A weight 161 counterbalances lever 158 to cause return movement thereof and closing of the valve 159 as soon as roller 128 rolls off of the outer free end of lever 130.

The washing operation progresses as the meter 139 advances the cam 127 until the roller 128 drops off of the free end of lever 130. This movement is timed to afford ample opportunity for thorough cleansing of the zeolite bed, and when the roller 128 drops off of the free end of lever 130 it strikes and depresses the lever 131, which in turn strikes a pin 162 extending laterally from a rod 163 which extends downward and is pivoted to a lever 164 of a valve 165 in the branch drain pipe 166 which communicates with the lower end of the cylinder 151. Lever 164 is counterbalanced by a weight 167 which causes the valve 165 to be closed as soon as the roller 128 drops off of the free end of lever 131, and the said counterbalancing weight 167 also moves

the rod 163 back up to its position for next operation.

It will thus be seen that when a regenerating operation is to be accomplished through the action of the timing mechanism just described, 5 the opening of valve 148 causes the rack 154 to swing the tank 99 to the substantially inverted position of Figure 13 where it remains until the roller 128 drops from lever 129. When this happens, the valve 159 being opened by the action 10 of rod 145 allows the water within cylinder 151 to drain back through the branch drain 160 for a distance sufficient to allow the piston 152 to descend that distance representing a return movement of tank 99 through 90° or from the 15 position seen in Figure 13 to the position seen in Figure 14. Then after the requisite time period allowed for rinsing or washing the salt out of the zeolites, the roller 128 dropping off 20 of lever 130 and onto lever 131 and thereby opening valve 165, allows a complete exhaustion of the water from the cylinder 151 with the resulting return movement of piston 152 to its initial position and the consequent return angular movement of tank 99 to its normal or upright position 25 as seen in Figure 12.

To facilitate and insure the return oscillation of the tank 99, a counterbalance weight 168 is carried by the lower, forward portion of the tank 99 in position to exert a stress tending to return 30 the tank to its upright position whenever it is free to move. A projection 169 is also preferably provided on tank 99 to serve as a detent and extends in the path of a stop 170 located to interrupt the return movement of tank 99 when the 35 tank reaches the vertical or upright position.

As above indicated, there may be need for water supply at a time when the service is interrupted by the salting or the cleansing operation, and to take care of such emergency need, a by-pass 171 is preferably provided extending from the supply main 111 past the tank 99 to and communicating with the house service pipe or other discharge pipe 104. To prevent water from flowing through the by-pass 171 while the tank 99 is in its normal or upright position, a valve 172 normally closes the by-pass 171 and the valve 172 is provided with a lever arm 173 having a weight 174 adapted to open the valve 172 whenever the valve is free to be opened. The valve, however, is provided with a second arm 175 which extends upward into the path of a pin 176 projecting laterally from tank 99, so that, whenever the tank returns from its inverted or inclined position to the upright position, the pin 176 will 45 strike the lever 175 and close the valve 172 against the pressure of the weight 174. Thus, the valve 172 is normally maintained closed by the pin 176, but will open under the action of weight 174 as 50 soon as the tank 99 begins to move under the actuation of the rack 154.

While the base exchange material has been diagrammatically indicated as made up of fairly large particles, it should be understood that relatively fine particles are preferred, because of the greater surface exposure for any given bulk being penetrated by water and the resulting more rapid treatment of the water, but the present invention is not to be limited to any particular size of particles or to any specific base exchange material, though zeolites are preferred in the form of relatively fine particles. The penetration of the zeolite bed by brine moving incident to difference in specific gravity between brine and water assures a regular, relatively slow advance and a 75

uniform penetration so that the zeolites are regenerated thoroughly and effectively.

Gear teeth 38 as seen in Figure 6 impart a complete revolution to cam 36 once in a predetermined period, say twenty-four or forty-eight hours, or other desired fixed period; but the cam advances by successive steps spaced by periods of inaction, so that the movement of the cam when it does move is substantially more rapid than the rate of movement which it would have to assume if it were to revolve in the same time period and be maintained in motion during the entire time. This increased speed of movement enables highly satisfactory and fairly accurate timing of the operations desired. For example, it not infrequently occurs that a washing operation only requires five minutes, whereas a salting operation for the same apparatus and process will require ten minutes or longer. Hence, the greater length of the portion 60 of lever 56 over the corresponding part of lever 57. Also, it should be noted that if the cam 36 makes one complete turn in twenty-four hours, that is fourteen hundred forty minutes, and the circumference travelled on the cam is say thirty-six inches, the distance travelled in five minutes would be five fourteen-hundred-fortieths of thirty-six inches, which equals a total of one-eighth of an inch or one-fortieth of an inch for each minute. This, of course, would represent a requirement of a too delicate adjustment for practical purposes, so that by advancing the cam with a step-by-step movement and having intermediate periods of non-action to make up the required twenty-four hours, or other time period, the relative movement along the surface of the cam can be considerably more rapid and afford a better opportunity for timing with satisfactory precision without such delicacy of adjustment. Thus, assuming the same time period as just above used illustratively, by the employment of the gear segment 38 with the gear 39 revolving once in three hours or eight times in twenty-four hours, the surface movement of the cam 36 will be as fast as one-fifth of an inch per minute or one inch in five minutes. Thus, opportunity is afforded for effective regulation of the timing for all practical purposes without such refinement and nicety of adjustment as is likely to get out of order or as requires excessive expense for production of precision of parts. The adjustability in the length of the respective portions 60 as shown and described with reference to Figures 21 and 22 is also valuable in facilitating the needed timing according to the particular apparatus and process to be carried out, including such elements as the thickness of the bed of zeolites and the coarseness or fineness of the grains thereof.

In Figures 23 to 27 inclusive is illustrated another embodiment in which the salt container, brine tank, and zeolite container are arranged as a unit instead of being separate containers as in Figure 1. Referring to the embodiment as seen in Figures 23 and 24 and related figures, 200 indicates a compartment for containing zeolites or like base exchange material, 201 a brine compartment, and 202 a salt compartment. These compartments are connected together to form a unitary structure, and one highly satisfactory and inexpensive form of such compartments consists 70 in the employment of a cylinder for each compartment with partitions 203 and 204 dividing the compartments, an upper header plate 205 closing the upper compartment, and a bottom header plate 206 closing the lower compartment. The 75 enclosure plates 205, 206 are preferably clamped

together as by through bolts 207 engaged by clamping nuts 208. The lower terminal portions of the bolts 207 are preferably enlarged to provide offset shoulders engaging the under face of the plate 206, and the enlarged lower extremities of the said bolts 207 therefore provide feet 209 on which the unit made up of the several compartments stands in use. The edges of the cylinders 200, 201, and 202 engage the partitions 203, 204 and end plates 205, 206 in a manner to produce 10 leak-tight joints therewith, which result may be accomplished by the use of appropriate gaskets or other sealing means. Rubber gaskets 210 have been found satisfactory for the purpose. In order to enable the said several cylinders to be 15 made of metal and still not be injured by contained solutions, I prefer to line each compartment with non-corrosive material, such as rubber 211.

A screen 212 is preferably fixed in the cylinder 20 or compartment 200 spaced above the bottom plate 206 sufficiently to leave a space 213, and a similar screen 214 is fixed to the compartment or cylinder 202 spaced above the partition 203 a distance sufficient to leave a space 215. A tube 216 extends from the upper end of the compartment 201 through partition 203 upward in compartment 202 to a point below the plate 205 and above the intended upper surface level of the salt or other regenerative agent 217 in the compartment. A tube 218 extends from the lower end of compartment 201 through partition 204 down within compartment 200, through screen 212, and communicates at its lower open end with the space 213. A tube 219 leads from the lower end 30 of compartment 202 and communicating with space 215 thereof through partition 203 down in compartment 201 to a point above the partition 204 and preferably in line with and above the upper end of the tube 218. A tube 220 leads from 40 the upper end of compartment 200 through the partition 204 and upward in compartment 201 to a point spaced below the partition 203. A valve 6a is provided for the upper end of tube 220 and is maintained in position for closing the tube at 45 all times except during the delivery of the regenerating agent to the zeolites 221 in compartment 200, which is called the salting operation and so indicated in the diagram of operation seen in Figure 27. A valve 5a is provided for the upper end of tube 218 and is positioned for maintaining the said upper end of tube 218 closed except during the said salting operation, as shown in the diagram of Figure 27. A valve 4a is provided in position for closing the said tube 219 at 50 all times except when the apparatus is being used for discharging treated water, or in other words, is performing its normal operation. Thus the valve 4a is closed during the salting operation and also during the cleansing or washing operation after 55 the regenerative action of the salt.

As best seen in Figures 25 and 26, each of the valves 6a, 5a, and 4a is like the other two in construction and consists essentially of a plate bearing a sealing cushion, such as a rubber pad 222. Pivotaly sustaining the plate of valve 6a is a link 223 which is pivoted to and depends from an operating arm 224, which for the greater portion of its length assumes the form of a hollow tube sustained in position to swing vertically by 70 a flexible connection to a portion of the wall of the compartment. This flexible connection may be of various modified forms, but one acceptable connection consists of an elastic sleeve, such as a rubber sleeve 225, engaging and supporting the 75

outer end of the tubular portion of the arm 224, the sleeve being flared outward to form a base 226 fixed to the inner surface of the wall of compartment 201. The sleeve 225 may be cemented 5 to the tubular portion of arm 224 and to the inner surface of the wall of compartment 201, or may be otherwise secured as preferred, but should be so connected as to prevent leakage. An opening 227 through the wall of compartment 201 10 is arranged in line with the bore of the tubular portion of arm 224, and a lever rod 228 extends from the exterior of compartment 201 through the aperture 227 into and along the tubular portion of arm 224. The outer extremity of the lever 15 rod 227 is pivoted at 229 to an operating link 230. Thus, when the link 230 descends the resulting rocking of the lever 228 causes the inner extremity of arm 224 to be lifted and the valve 6a correspondingly lifted to an open position with reference to the tube 220.

As seen in Figure 26, the valves 4a and 5a are pivoted at 231 to the same tubular arm 232, the valve 4a being arranged to upstand from its pivot 231, and the valve 5a to depend therefrom. The 25 tubular arm 232 is connected by an elastic sleeve 233 and its flared outer portion 234 to the wall of the compartment 201 in the same manner as described above with respect to the arm 224 and its connection. An aperture 235 is formed in the 30 wall of the compartment 201 in line with the bore of arm 232, and a lever rod 236 extends through said aperture into the arm to operate the same. The outer terminus of the lever rod 236 is pivoted at 237 to the operating link 238, so that, when the 35 link is raised, the valve 5a will be seated on the upper end of and close the tube 218, and when the link 238 is moved downward the valve 4a will be raised and seated against the lower end of tube 219 for closing said tube. Each of the lever rods 40 228 and 236, of course, acts against the wall of compartment 201 as a fulcrum at the place of the respective opening 227 or 235.

A pipe 8a leads from the street main or other source of supply, is provided with a valve 1a, 45 and communicates with the upper end of the compartment 200 above the zeolite bed 221. A pipe 13a leads from the space 213 at the lower end of compartment 200 to deliver treated water for use. A pressure valve 14a is provided in the 50 length of pipe 13a to prevent the flow of water in the pipe 13a except under pressure, so that the valve 14a seats automatically whenever the street or main pressure is relieved from within the compartment 200. A branch 10a leads from pipe 55 8a outward beyond valve 1a to the upper end portion of compartment 201, and a valve 2a controls the flow in the branch 10a. A drain pipe 12a communicates with the pipe 8a at a point nearer the compartment 200 than the location of 60 valve 1a, and a valve 3a controls the discharge through the drain 12a. The valves 1a and 3a are actuated by links 54a in one direction, and are stressed to return after an impulse imparted by links 54a either by the provision of springs or 65 weights, not shown, but corresponding to the weights 32 and 34 of Figure 1. The links 54a are pivoted to an actuating rod 52a substantially identical in form and function with the rod 52 of the structure seen in Figure 1. The valve 2a 70 is actuated in one direction by link 55a and is given its return impulse either by a spring or weight, not shown, but corresponding to the weight 33 of the structure seen in Figure 1. The link 55a is pivoted to and actuated by a rod 53a 75 corresponding in form and function with the rod

53 of Figure 1. A timing mechanism, including a timing cam 36a and its cooperating parts, actuate the rods 52a and 53a as described above with respect to cam 36 and its cooperating parts. Included in the said cooperating parts of the timing mechanism are the levers 56a and 57a located and functioning in the same manner as levers 56 and 57 relative to the actuating parts of the valves 1a, 3a, and 2a. The operating rod 52a has an upward extension 63a which is pivotally connected 10 to and rocks a rock shaft 239 having a crank arm 240 pivotally connected to the link 238. Thus, when the actuating rod 52a descends to actuate valves 1a and 3a, it at the same time rocks the shaft 239 to shift link 238 downward 15 and thereby unseat the valve 5a and seat the valve 4a. Also, a link 241 is pivoted at 242 to the lever 56a at the lower end of the link. Link 241 upstands from lever 56a and at its upper end is pivoted to a crank carried by a rock shaft 20 243, which rock shaft carries a crank 244 engaging the link 230 for depressing the last-named link and thereby raising the valve 6a when the actuating rod 52a descends for the first half of its full stroke. It will be noted that the weight 25 which depresses lever 56a on passing beyond said lever and engaging the lever 57a while releasing lever 56a to rise under the pressure of its return spring does not release rod 52a for an upward movement owing to the detent afforded by the 30 fingers 68a and 69a, the latter overlapping the former in a manner to cause the rod 52a from having a return stroke while the link 53a is in its lowered position.

Thus, the structures seen in Figure 23 and 35 its associated figures will operate substantially after the manner described with respect to the structure seen in Figure 1 but following the details of the sequence indicated in the chart of Figure 27.

Of course, it is understood that the salt 217 is first supplied to the compartment 202 and the 45 bed of zeolites 221 is likewise supplied to the compartment 200. This may be done before the several compartments are assembled in the unitary form. Subsequent supplies of salt are preferably introduced through an opening 245 closed by an appropriately threaded plug or other detachable cap 246. Also, the upper compartments are supplied with water to produce the 50 required brine and a saturate solution is formed and accumulates by difference in specific gravity in the compartment 201. Meanwhile, the zeolites 221 may be functioning. The normal or regular operation of delivering softened water 55 merely consists of the flow of water through the pipe 8a to the upper end of compartment 200, percolation of such water through the zeolite bed 221 to the space 213, and thence out through pipe 13a, valve 14a being held open for such 60 discharge by the pressure of the incoming water. Thus, during the normal operation, the parts are in the position seen in Figure 23 with valve 1a open, valve 2a closed, valve 3a closed, valve 4a open, and valves 5a and 6a closed, all as shown in 65 the chart, Figure 27, under the heading "normal". As the zeolites approach the period of approximate exhaustion and the cam 36a is completing or has just completed a revolution, the weighted part drops from the greater diameter of the cam 70 onto the lever 56a which, in descending, imparts a thrust to the rod 52a that closes the valve 1a and opens the valve 3a. As the rod 53a has not been moved, the valve 2a remains closed. The downward movement of the rod 52a, however, im- 75

parts angular movement to the rock shaft 239 that causes the rod 238 to descend, and the drop of link 241 causes the rock shaft 243 to move link 230 downward, whereby the valve 6a is opened, 5 valve 5a is opened, and valve 4a is closed, all as shown in the chart of Figure 27 under the heading "salting". The parts maintain this position during the regeneration of the base exchange material which is accomplished by the 10 descent of the saturate solution from compartment 201 through the tube 218 to the space 213, and the percolation of the said solution up through the zeolite bed 221. This movement of the saturate solution is occasioned by the difference in 15 specific gravity between itself and the water contained in the space 213 in the zeolite bed and in the space above the zeolite bed, and in tube 220. As the valve 4a is closed liquid in compartment 202 can not descend into compartment 201 and 20 the interchange, therefore, occurs between the compartment 201 and the compartment 200. It will be readily understood that with the closing 25 of the valve 1a, which cuts off pressure from the compartment 200, the valve 14a will automatically close so that there is no danger of salt finding its way into the pipe 13a. When the salting operation has terminated, the weight drops from lever 56a onto lever 51a and the lever 56a returns to its normal, raised position. This upward movement 30 causes a reverse movement of shaft 243 and a lifting of the link 230 which results in the seating of the valve 6a on the upper end of tube 220. But the descent of lever 57a carrying with it the rod 53a causes the finger 69a to serve in co- 35 operation with finger 68a as a detent preventing a return movement of the rod 52a so that the link 238 can not ascend to open valve 4a or close valve 5a. Wherefore on the descent of the rod 53a under the impulse from the lever 57a the 40 several valves will have the position indicated in the chart of Figure 27 under the heading "washing". That is to say, valve 1a will remain closed, valve 2a will be opened, valve 3a will remain open, valve 4a will remain closed, valve 5a 45 will remain open, and valve 6a will be closed. While the parts are in this position water will pass from pipe 8a, through branch 10a to the upper portion of the compartment 201, forcing the brine ahead of it down through pipe 218, up 50 through the bed of zeolites, and out through pipe 8a to the branch 12a, and out through the branch past valve 3a to the drain. This flow continues until all of the salt solution is removed from the zeolite compartment 200 and from the compartment 55 201. At the conclusion of the washing operation, the weight drops off of the lever 57a and begins its travel along the surface of cam 36a allowing the lever 57a to make its return stroke, so that rod 53a rises and permits rod 52a 60 to rise, whereby the valves are returned to their normal position as indicated in the last line of the chart of Figure 27, wherein the valve 1a is open, valves 2a and 3a are closed, valve 4a is open as seen in Figure 23, and valves 5a and 6a are 65 closed. Thus, the cycle is completed and the normal operation of discharging softened water through pipe 13a begins again, as the water descends from pipe 8a through the bed 221 to the 70 pipe 13a under pressure sufficient for opening the 75 valve 14a.

It will be observed that during the salting operation by a difference in specific gravity displacement having occurred and the clear water from compartment 200 having been caused to 75 enter compartment 201 through pipe 220, so

likewise when the valve 4a is opened and valve 5a is closed (valve 6a having been closed) a further displacement by difference in specific gravity occurs and the brine that has been forming in the space 215 as well as in the bed of salt 217 descends through pipe 219 to the compartment 201 and displaces the water therein causing it to move up through the tube 216 to replace the liquid (brine) leaving the compartment 202, and the thus delivered water in descending through the bed 217 10 itself becomes a brine preparatory for the next operation.

It will be noted that throughout the several embodiments where arrows are employed to show travel of liquid, the single headed arrow indicates clear water or clear liquid, and the double-headed arrows indicate wash water or cleansing fluid and exhausted brine.

It will also be noted that in the operation of the timing mechanism in each instance, the cam 36, or its equivalent cam, and gearing 37 and 38 which actuate the cam are set with respect to each other such that roller 41 drops off of the greatest radius of the timing cam at the beginning of an intermeshing stroke of gear 38 with gear 37, so that both the salting and the rinsing operations are completed by a single action of gear teeth 38 in one stroke of intermesh with gear 37, and the periods of non-movement of the timing cam are all in the period of normal operation of liquid treatment, that is flow or freedom to flow of the supply of softened water.

The timing of the softening operation, salting operation, and washing operation will correspond of course to the size and work required of the bed of zeolites, including as a factor the extent of fineness of the grains of zeolites to insure complete regeneration with each salting operation to give the greatest softening capacity to the bed of zeolites of which it is capable, and the exhausted salt solution is thoroughly washed away to insure the delivery of only good, clear softened water through the service pipe, and, accordingly, the mechanism controlling the timing is important and must function with a substantial degree of precision and dependability. The mechanisms above described are capable of thus functioning, and, of course, other equally efficient timing mechanisms may be used having greater or less requirements for nicety of adjustment of parts 50 according to the demands on the particular water softening plant. A form of timing mechanism somewhat different from that above described, but incorporating the same principle and yet affording a greater opportunity for movement of the moving parts, and thus still further reducing the necessity for nicety of adjustment is shown in Figures 28 to 31 inclusive of the accompanying drawings in which a stationary support or frame 250 is provided having an inclined surface 251 over which is adapted to ride a weight 252 having a roller 253 for travelling on the surface 251. The weight is designed to ride up the inclined surface 251 to its highest point and then drop off onto a lever 254 which corresponds in its form, function, operations, and connections to either lever 56 of Figure 6 or lever 56a of Figure 23, or may function the same as the corresponding lever of the structure seen in Figure 9; and after the weight 252 leaves the lever 254 and allows the 60 same to rise it drops onto a lever 255 which corresponds in its form, function, operations, and connections with lever 51 of Figure 6, or lever 51a of Figure 23, or to the corresponding lever of the structure seen in Figure 9. Each of levers 254 65

and 255 is appropriately pivoted to the support or frame 250. The valve actuating rods or bars 260 and 261 corresponding to the bars 52 and 53 respectively of Figure 1 and corresponding bars 5 of the other figures are actuated respectively by levers 254 and 255 in the same manner and for the corresponding result as the actuation of the bars 52 and 53. The parts with which bars 260 and 261 are connected are omitted for the saving 10 of space, but it will be readily understood that they are the same as those shown in the above-mentioned figures of the drawings with which the corresponding parts of said figures cooperate.

The weight 252 is preferably actuated by an 15 endless belt and is connected in the length of the belt as a part of the same so as to travel a distance sufficient to consume the time corresponding to the time during which the normal operation of water softening is to be carried out between the spaced operations of restoration of the 20 zeolites to their capacity to soften water. By sufficiently lengthening the endless belt, the travel of the weight 252 along the end portions of the levers 254 and 255 may be increased to any extent 25 desired and proportionally decrease the necessity for nicety of adjustment in view of the increased time required for the travel of the weight along the engaged portion of the respective lever. The endless belt may assume any of various forms and 30 may be passed about any appropriate supporting pulleys or guides and driven from any convenient source of power having the requisite uniformity of movement of the belting in mind to insure satisfactorily accurate timing. For instance, the 35 belting may consist of a pair of sprocket chains 256 engaging sprockets 257 driven by an electric motor 258, or driven by the interchanging source of power shown in Figure 10. Idler sprockets 259, 259, may be arranged in any convenient order, such as that seen in Figure 28, to afford provision for the requisite length of belting. Each pair of sprockets 259 corresponds in form and spacing to the sprockets 257 to accommodate the passage of the weight 252 therebetween, so 45 that the belt 256 is free to move continuously at an established rate to cause the weight to reach the place for dropping off of the support 250 and onto the lever 254 in proper timed relation to the functioning of the water softening apparatus and 50 its cooperating parts, as above described.

As clearly seen in Figure 29, the support or frame 250 is of a width sufficiently narrow to allow the chains making up the belting 256 to extend at the opposite sides of the said frame, so 55 that the said chains may drop down below the level of the surface 251 when the weight 252 drops successively onto levers 254 and 255. The belting 256 contains a sufficient amount of slack to allow for sagging between uppermost idler sprocket 259 and sprocket 257 for permitting the weight 252 to drop to the dotted line position seen in Figure 28, and thereby operatively lower the lever 255. The dotted line position of Figure 28 is, of course, idealized, and, in fact, in practice there will be 60 some looping or sagging of the chain below the planes indicated by the dotted lines at the opposite sides of the weight to take up the excess chain length required to allow the weight to pass above the highest point of the support or frame 250. Also, the reaches of the belting between sprockets 65 257 and the first set of sprockets 259 and between opposing sprockets 259 are shown as perfectly straight, whereas, of course, there will be some sagging and looseness, a large portion of which 70 will be preferably prevented by supporting anti-

friction rollers 262 located in sufficient proximity to each other to insure each upper reach of belting from sagging down into interference with a lower reach, and also to insure the required looseness to allow the weight 252 to drop onto the successive levers 254 and 255. 5

By employing the belting 256 of the requisite length and appropriately mounting the same whether with the circuitous route shown in Figure 28 or otherwise, a longer distance of contact 10 of the weight 252 with the successive levers 254 and 255 may be afforded with a continuously, uniformly moving belt while allowing a sufficient time to elapse between the dropping of the weight 252 onto lever 254 at one time and its next dropping onto said lever to represent the total period 15 during which the zeolites are intended to function for softening water before being again treated for regeneration. For example, if the endless belting 256 is, say forty-eight feet long, 20 that is five hundred seventy-six inches, and the period of the complete cycles of operation including the water softening or normal operation, the regenerative operation, and the washing operation are to require twenty-four hours, that is 25 fourteen hundred forty minutes, then the weight 252 will travel two inches in five minutes, so that, if the washing operation requires five minutes, the weight will travel along two inches of the outer end portion of the lever 255 during the washing operation, and, of course, the salting operation will be represented by a proportionally longer period enabling a proportionally longer portion 30 of lever 254 to be travelled by the weight 252, whereby necessity for nicety of adjustment is 35 proportionally reduced.

It is, of course, desirable to limit the descent of the cam-carried levers to the intended extent, and, therefore, it is preferable to provide stops similar to stops 62 wherever such limitation is 40 needed, and, to that end, a stop 62b is provided on the cam 36a, as seen in Figure 23, and a stop 62c is provided on the frame 251, as seen in Figure 28, for limiting the extent of downward movement 45 of the upper lever.

As a matter of generalization of certain features of the present improved apparatus and process, it will be readily recognized as desirable to have an excess of zeolites, which is a provision in the nature of a margin of safety, so that there 50 will be no danger of actual complete exhaustion and resultant discharge of non-softened water. This amount of excess can be in any appropriate and convenient quantity within the limits of reasonable available space. For example, one cubic 55 foot of zeolites weighing fifty pounds will extract 12,500 grains of calcium carbonate (CaCO_3), the hardening element, from water, so that if the water contains ten grains per gallon (an average condition) then one cubic foot of zeolites will 60 safely treat 1,250 gallons before requiring regeneration. But as the calcium carbonate will vary from ten to twenty grains per gallons of water at different seasons of the year, it is desirable to use an excess of the zeolites, say two 65 cubic feet for each 1,000 gallons of water to be softened. Where there is known less variation in the calcium carbonate content of the water the excess of zeolites can, of course, be reduced.

It will also be observed that while the difference in specific gravity as the force for distribution of the saline solution to the zeolites is desirable both because of facility and because of extent of effective penetration in its advance in and through the bed of zeolites, the same 70

distribution can be obtained by the delivery of the saline solution by other force, such as a hydraulic head throttled or restricted down low enough to cause the advance of the saline solution into the zeolite container and into the bed of zeolites to be sufficiently slow for effective distribution and permeation and to give time for the desired regenerating actions; but it is important to employ the force of difference 10 in specific gravity to build up a supply of saline solution preparatory for regeneration of the zeolites during the period when water is being passed through the zeolites in the regular softening operation. By this mode of providing for 15 the supply of salt solution no time is lost, the action is entirely automatic, and the quantity of salt supplied can be measured with a very satisfactory degree of nicety so far as required for insuring complete regeneration without un- 20 due or any substantial waste of salt. Of course, while the salt solution has been herein referred to as a saturate solution, it should be understood that it is not saturate to the point where crystallization of the salt out of the solution is likely 25 to occur. But it is only an approximately saturate solution, that is saturate to the point of having that degree of brine richness enabling accuracy of measurement but not likely to result in the formation of salt crystals because a full 30 saturate solution might result in crystallization at such places as the disc valves with resulting interference in the efficient or accurate operation of the parts. The accumulation of a measured quantity of this approximately saturate salt 35 solution by the gravity action is effective in providing for the desired economical use of salt with no extra effort or expense and with dependably assured results.

What is claimed is:—

- 40 1. In timing mechanism for liquid treatment apparatus, the combination with liquid treatment controlling apparatus including circulation conduits and valve means therefor, of a gravity-actuated weight for operating the valve means, and means comprising a gradually ascending camway for moving the weight back to its initial operating position after a valve operating action of the weight, and means for operating the camway to intermittently raise the weight.
- 45 2. The combination as claimed in claim 1 in which the camway comprises a series of stepped surfaces for dividing the stroke of the weight in its descent into successive actuating movements for successive control operations of the valve means.
- 50 3. In timing mechanism for liquid treatment apparatus, the combination with containers for base exchange and regenerative substances, circulation conduits, and valve means therein, of a variable radius cam having an abrupt shoulder leading from the maximum to the minimum radius of the cam, a weight resting on the periphery of the cam and elevated thereby incident to revolution of the cam, and control means for said liquid treatment apparatus carried by the cam and arranged in stepped relation and actuated by descent of the weight from the maximum radius of the cam toward the minimum radius thereof, said control means being arranged to operate the valve means when actuated by said weight.
- 55 4. In liquid treatment apparatus for treating liquid by contact with base-exchange material, the combination of aligned tubular cylinders, terminal plates and partition plates closing and di-

viding said cylinders to provide a base-exchange material compartment, a regenerative agent compartment, and a measuring compartment for the regenerative agent, means securing said parts together in the form of a unit, and automatic 5 means for establishing circulations between said compartments in regenerating and treating cycles, comprising a rotatable operating cam, levers carried by the cam, a weight to actuate said levers, valves controlling the flow of fluids 10 to and from the several compartments and actuating means between the levers and valves.

5. In water softening apparatus, the combination of a structure comprising a series of superimposed compartments, the lowermost of 15 which is adapted to contain base-exchange material for the treatment of liquid, the second or next higher compartment being adapted to contain regenerative agent, and the third compartment or compartment above the regenerative 20 agent compartment being adapted to contain material to be dissolved to produce the regenerative agent, a tube extending from the lower portion of the second compartment to the lower portion of the base-exchange material compartment, a tube extending from the upper portion of the base-exchange material compartment to the upper portion of the second compartment, a tube extending from the lower portion of the third compartment to the lower portion of the 25 second compartment, valves for closing said tubes, a tube extending from the upper portion of the second compartment to and communicating with the upper portion of the third compartment, means for supplying liquid to be 30 treated to the upper portion of the base-exchange material compartment, means for supplying liquid to the second compartment, a drain pipe communicating with the upper portion of the base-exchange material compartment, valves 35 controlling said drain and said liquid supply means, a discharge pipe for treated liquid leading from said base-exchange material compartment, means for actuating all of said valves relative to each other for cutting off the supply 40 of liquid to be treated to the base-exchange material compartment, closing the tube leading from the lower portion of the third compartment into the second compartment, opening the tube leading from the lower portion of the second compartment to the lower portion of the 45 base-exchange material compartment, and opening the tube leading from the upper portion of the base-exchange material compartment to the upper portion of the second compartment, and 50 maintaining the valves in such position for allowing regenerative agent to descend into the base-exchange material compartment and to rise therein to displace by difference in specific gravity the liquid in the said base-exchange material compartment and cause it to move up 55 through the tube leading from the base-exchange material compartment to the upper portion of the second compartment, for then closing the tubes leading from the base-exchange material compartment into the second compartment and from the second compartment into the base-exchange material compartment, and opening the tube leading from the lower portion of the third compartment into the second compartment, for 60 opening the valve admitting liquid to the second compartment and opening the valve to the drain from the base-exchange material compartment, and finally for closing the last two 65 named valves and opening the valve controlling 70 75

the supply of liquid to be treated to the base-exchange material compartment, and means for timing the said valve actuating means for maintaining the sequence of operation stated.

5 6. The combination as claimed in claim 5 with means for controlling the said timing means for maintaining the positioning of the said valves for allowing delivery of regenerative agent to the base-exchange material compartment for a period of time of a different length from the period of time of the maintaining of the valve in an open condition delivering liquid to the second compartment.

7. In apparatus of the class described, the combination of a base-exchange material container, a regenerative liquid container located at a higher elevation than the first mentioned container, means of communication between the two containers comprising tubular means, a valve in one of said containers for controlling said communication, and lever means extending through the wall of one of the containers for actuating the valve.

8. In timing mechanism for liquid treatment apparatus, the combination of control means for liquid treatment apparatus including a plurality of valves and operating rods therefor, a weight arranged to drop in a vertical plane for actuating the rods, means having a camway arranged on a varying radius for returning the weight to the actuating position after drop thereof and means to operate said camway.

9. The combination as claimed in claim 8, wherein the means for operating the camway operates intermittently and the camway returns the weight with a step-by-step movement with intervals of time between steps.

10. The combination as claimed in claim 8, wherein the weight-returning camway moves the weight with a continuous, uninterrupted movement.

11. In timing mechanism for liquid treatment apparatus, the combination of control means therefor, including a plurality of valves and operating rods, a weight arranged to drop in a vertical plane for actuating the rods, means for returning the weight to actuating position after drop thereof including a camway and an endless belt in combination with means for continuously actuating the belt.

50 12. A cyclic system for softening water comprising a container for holding zeolite, a container for holding a regenerative substance arranged above the zeolite container and a container for holding a measured quantity of solution of said substance below the regenerative substance container and above the zeolite container, a conduit connecting the top of the zeolite container with the top of the solution container, a valved conduit connecting the bottom of the solution container with the bottom of the zeolite container, a conduit connecting the top of the regenerative substance container with the top of the solution container, and a valved conduit connecting the bottom of the regenerative substance container with the bottom of the solution container, said conduits and containers forming closed circuits between the respective containers, means for supplying water to the circuit between the regenerative substance container and the solution container to form a static column of water and a parallel column of regenerative solution and a water column between the zeolite container and the solution container, and means for effecting flow of water through the zeolite and

simultaneously opening the valves of the valved conduits aforesaid to release the columns of the closed circuit between the regenerative substance container and the solution container to permit flow of the regenerative solution to the solution container to provide a measured quantity of the solution therein by a difference in the specific gravity of the water and regenerative solution columns in the said circuit.

5 13. A system as set forth in claim 12 wherein said flow effecting means is automatically operative in cycle to discontinue the flow of water through the zeolite container and establish flow of the measured quantity of regenerative substance in the circuit between the solution and zeolite containers by the difference of specific gravity of the liquids in said last mentioned circuit.

14. In cyclic water softening apparatus, a zeolite container, a salt container above the same, and an intermediate salt solution container, conduits connecting the bottom of the solution container with the bottoms of the zeolite and salt containers, and other conduits connecting the top of solution container with the tops of the zeolite and salt containers, said containers and conduits forming two normally closed circuits, one between the salt and solution containers and one between the solution and zeolite containers, a water supply conduit connecting with said intermediate container for flowing water to either of said circuits, to form salt and water columns in each of said circuits, and to and from the zeolite container for softening the water, valves arranged in said circuits, and means for automatically operating the valves in cycles to effect a flow of salt solution to the solution container by a difference in the specific gravity of the salt solution and water columns in one circuit and a flow of the solution from the solution container to the zeolite container by the difference in the specific gravity of the columns of liquids in the other circuit.

15. Apparatus as set forth in claim 14, wherein the supply conduit to and from the zeolite container is provided with valve means operated by the automatic means for discontinuing flow of water through the zeolite during the cycle of gravity flow of liquids in the closed circuit between the solution and zeolite containers for regenerating the zeolite and for effecting flow of the water through said circuit during another cycle for washing the zeolite.

16. In a liquid treating apparatus of the class described, the combination of a zeolite tank, a salt tank, means for flowing water to be treated through the zeolite tank, conduits between the two tanks forming a closed circulation system including valve means for preventing circulation between the salt and zeolite tanks during liquid treatment in the latter, means for introducing water into said circulation system to form a salt solution column and a water column in said system while treating the water by the zeolite, and automatic means to cut off the flow of water through the zeolite and operate the valve means aforesaid and establish circulation in said closed system to effect transfer of the salt solution to the zeolite tank by the difference in the specific gravity of the salt solution column and the column of water.

17. In a liquid treatment apparatus of the class described, the combination of a zeolite tank, a salt tank, one of said tanks being disposed at a higher elevation than the other, means for flow-

ing water through the zeolite tank to treat the same, conduits between said tanks forming a closed circulation system including means for delivering salt solution to the zeolite tank in measured quantity corresponding to the amount required by the zeolite tank, means for introducing water into said closed circulation system to form a brine column and a parallel water column during the water treatment, means in said system for maintaining said columns during water treatment, and means to automatically cut off the flow of water to the zeolite tank and operate the column maintaining means to permit the brine to move to the zeolite tank by difference in specific gravity of the two columns to effect regeneration of the zeolite.

18. In a liquid treatment apparatus of the class described, the combination of a zeolite tank, a salt tank, one of said tanks being disposed at a higher elevation than the other, conduits between said tanks forming a closed circulation system, means for introducing water into said circulation system to form a brine column and a parallel water column during flow of water through the zeolite tank, means in said system for maintaining said columns during said flow, and means to automatically cut off the flow through the zeolite tank and operate the column maintaining means to permit the brine to move to the zeolite tank by difference in specific gravity of the two columns to effect regeneration of the zeolite, said zeolite tank being sufficiently below the salt tank to cause the zeolite tank to be filled with the brine upon equalization of the average specific gravities of the two columns.

19. In a liquid treatment apparatus of the class described, the combination of a zeolite tank, a salt tank, means for flowing water to be treated through the zeolite tank including means for cutting off the flow thereof, conduits between the two tanks forming a closed circuit, means for introducing water into said circuit to form a brine solution column in which the salt tank is disposed and a water column in which the zeolite tank is arranged, means for maintaining said columns during treatment of the water by zeolite, and control means for operating the water cut off means and simultaneously releasing the said liquid column maintaining means to thereby effect transfer of the brine solution from the salt tank to the zeolite tank and water from the zeolite tank to the salt tank by the difference in the specific gravities of the brine and water columns, said transferring action ceasing as a result of the equalization of the average specific gravities in the two columns of the closed circuit.

20. In a liquid treatment apparatus of the class described, the combination of a zeolite tank, a salt tank, means for flowing water to be treated through the zeolite tank, conduits between the two tanks forming a closed circuit, means for introducing water into said circuit to form a brine solution column in which the salt tank is disposed and a water column in which the zeolite tank is arranged, a measuring receptacle arranged in said circuit for holding a predetermined quantity of brine solution, means in said receptacle for maintaining the columns of liquids in said circuit quiescent during flow of the water through the zeolite tank, and common control means for discontinuing the water flow and operating the column control means to effect delivery of the measured quantity of the brine to the zeolite tank to effect regeneration of the zeolite and trans-

fer of the water in the zeolite tank to the salt tank by the difference in the specific gravity of the two columns.

21. In a liquid treatment apparatus of the class described, the combination of a zeolite tank, a salt tank, means for flowing water to be treated through the zeolite tank, conduits between the two tanks forming a closed circuit, means for introducing water into said circuit to form a brine solution column in which the salt tank is disposed and a water column in which the zeolite tank is arranged, a measuring receptacle arranged in said circuit for holding a predetermined quantity of brine solution, means in said receptacle for maintaining the columns of liquids in said circuit quiescent during flow of the water in the zeolite tank, and common control means for discontinuing the water flow and operating the column maintaining means to effect delivery of the measured quantity of the brine to the zeolite tank to effect regeneration of the zeolite and transfer of the water in the zeolite tank to the salt tank by the difference in the specific gravity of the two columns, said last named means being automatically operable at a predetermined time to interrupt the transfer action in the circuit aforesaid and effect flow of water through the zeolite tank to remove the brine solution therefrom and replenish the brine solution in said circuit.

22. That improvement in the art of softening water through the agency of a gravity circulation system including a container for holding zeolite, containers for holding salt and brine, and circulating conduits forming a closed circuit between said containers which consists of the steps of flowing the water through the zeolite container for a predetermined length of time while building up a column of water and a column of salt solution, and utilizing the difference in the average specific gravity between the column of salt solution and the column of water in the closed circuit to transfer the salt solution from the brine container to the bed of zeolite while transferring the water from the zeolite container to the salt container in a timed relation sufficient to regenerate the zeolite proportionate to its exhaustion.

23. That improvement in the art of softening water through the agency of a gravity circulation system including a container for holding zeolite, a container for holding salt, circulating conduits forming a closed circuit between said containers which consists of the steps of flowing the water through the zeolite container for a predetermined length of time while building up a column of water and a column of salt solution, utilizing the difference in the average specific gravity between the column of salt solution and the column of water in the closed circuit to transfer the salt solution from the salt container to the bed of zeolite while transferring the water from the zeolite container to the salt container in a timed relation sufficient to regenerate the zeolite proportionate to its exhaustion, and utilizing the resultant equalization of the average specific gravities in the two columns to cause cessation of the transferring action.

24. That improvement in the art of regenerating zeolite in a water softening system, including a closed circuit for holding a brine column and a water column, a brine tank in the upper part of said circuit, and a zeolite tank in the bottom part of said circuit which consists in utilizing the difference in the average specific gravities of the two columns of liquid in said circuit for the

purpose of transferring brine from the brine tank to the zeolite tank.

25. That improvement in the art of regenerating zeolite in a water softening system, including a closed circuit for holding a brine column and a water column, a brine tank in the upper part of said circuit, and a zeolite tank in the bottom part

of said circuit which consists in utilizing the difference in the average specific gravities of the two columns of liquid in said circuit for the purpose of transferring brine from the brine tank to the zeolite tank and transferring water from the zeolite tank to the brine tank. 5

GEORGE MOORE.
